UNITED STATES PATENT OFFICE.

FRANK J. FARNER, OF SEATTLE, WASHINGTON, ASSIGNOR OF ONE-HALF TO JOHN J. MURRAY, OF SEATTLE, WASHINGTON.

BOTTLE-STOPPER.

No. 890,506.

Specification of Letters Patent.

Patented June 9, 1908.

Application filed October 23, 1907. Serial No. 398,809.

To all whom it may concern:

Be it known that I, FRANK J. FARNER, a citizen of the United States, residing at Seattle, in the county of King and State of Washington, have invented new and useful Improvements in Bottle-Stoppers, of which the following is a specification.

This invention relates to bottle stoppers or closures, its primary object being to provide a stopper which may be conveniently applied and will operate to effectually seal the bottle against leakage, and yet may be readily extracted without the use of a special form of tool.

15 A further object of the invention is to provide a construction of bottle neck and stopper, whereby the stopper upon application may be expanded and crowded into interlocking engagement with a groove in the 20 neck in such a manner as to be firmly held against displacement and to effect a hermetic seal, and further to form a stopper of sufficiently soft material to enable it to be punctured, cut out or extracted without the 25 necessity of employing any peculiar form of tool for the purpose.

The invention consists of the features of construction, combination and arrangement of parts hereinafter fully described and 30 claimed, reference being had to the accompanying drawing, in which:

Figure 1 is a vertical transverse section through the upper end of a bottle neck sealed by the improved stopper. Fig. 2 is a 35 similar view of the neck with the stopper detached. Fig. 3 is a cross-sectional view of the stopper as it appears prior to application. Fig. 4 is a top plan view of the same.

Referring to the drawing, 1 designates a 40 bottle-neck formed with a filling and discharge passage 2 of ordinary or any convenient form. Near the top of this passage is arranged a horizontal shoulder 3, forming the lower wall of an annular groove 4, the 45 upper wall 5 of which is beveled or inclined inwardly and upwardly until it intersects the wall of the passage close to or adjacent the upper end of the neck.

The stopper constituting one of the essential features of the invention may be composed 50 of soft metal, paper or any other suitable pliable material, or of a combination of two or more of such materials, and is primarily cut out in the form of a disk 6 of circular or of 55 any other convenient form. This disk is

then shaped in any preferred manner to upset or roll the edge thereof, as indicated at 7, forming a stopper of cup-form and sufficiently contracted in diameter to enter the neck and rest upon the extreme outer edge of the shoulder 3 with the rolled rim or flange 7 bearing slightly against the wall 5 and projecting partially into the groove 4. The marginal edge of the rolled flange or rim may be turned inwardly and downwardly into the mouth of the cup-shaped stopper thus formed, as indicated at 8, so as to provide an increased extent of rolled surface to permit expansion to any necessary degree to effect a tight filling and closure of the groove 4 and a firm interlocking engagement with the walls thereof.

After the bottle has been filled, the stopper contracted as above described is inserted into the bottle neck until it rests upon the outer edge of the shoulder 3, when, through the action of a suitable type of tool or machine, the rolled flange or rim is spread outwardly or expanded into the groove 4. By this operation the flange or rim is to a greater or less extent unrolled and crimped until the marginal portion 8 lies close to or in contact with the body of the flange 7, thus bringing the stopper into engagement with all points of the surfaces of the walls 3 and 5 and interlocking it securely with the wall of the body.

The pliable character of the material of which the stopper is made adapts it to so closely fill the groove as to hermetically seal the neck against the leakage of any confined liquid or gas, and, as the portion of the unrolled rim lying in contact with the beveled shoulder 5 is reinforced by the crimped marginal edge 8, it will be apparent that the firm bearing of the stopper against said shoulder 95 will effectually prevent displacement of the stopper against great internal pressure.

Of course, the form and arrangement of the parts within the scope of the invention as defined in the appended claims may be varied, but the construction in general as herein shown and described is preferred for general use and will provide an effective seal under all ordinary conditions. The character of the material, in addition to the advantages 100 before set forth, adapts the stopper to be punctured, cut out or extracted by implements in ordinary every day use, thus obviating the necessity of employing a special form of extracting tool.

Having thus described the invention, what I claim as new is:—

1. A bottle stopper comprising a substantially flat body or disk of pliable material, said disk having its marginal portion bent or rolled upwardly and inwardly to impart to the stopper a cup-form, the edge of the rolled margin being inturned into the body of the cup and forming a rim of generally circular form in cross-section and adapted to be spread and crimped into a substantially triangular form.
2. A bottle neck provided with an annular groove having a horizontal bottom wall and an upwardly and inwardly beveled top wall, said walls having their inner edges flush with the inner wall of the neck, and a stopper having a rolled rim spread into the groove and

crimped into triangular form into interlocking engagement with said walls.

3. A bottle neck provided with an annular groove having a horizontal bottom wall and an upwardly and inwardly beveled top wall, and a stopper of pliable material comprising a body or disk resting upon the bottom wall and having an upwardly and inwardly rolled inner edge provided with a pendent flange, said edge and flange being spread into the groove and into interlocking engagement with said beveled top wall.

In testimony whereof I affix my signature in presence of two witnesses.

FRANK J. FARNER.
